UNITED STATES PATENT OFFICE.

THOMAS F. HARRIS, OF ANNISTON, ALABAMA.

COMBINED LEAD-PENCIL AND SHARPENER.

SPECIFICATION forming part of Letters Patent No. 531,081, dated December 18, 1894.

Application filed October 11, 1894. Serial No. 525,555. (No model.)

To all whom it may concern:

Be it known that I, THOMAS F. HARRIS, a citizen of the United States, residing at Anniston, in the county of Calhoun and State of Alabama, have invented certain new and useful Improvements in a Combined Lead-Pencil and Sharpener; and I do hereby declare the following to be a full, clear, and exact description of the invention, such as will enable others skilled in the art to which it appertains to make and use the same.

My invention relates to improvements in combined lead pencils and sharpeners therefor, and the same consists of a pencil made with the lead loose therein, provided with means for gripping the lead when in use, and having normally seated at its rear end an improved detachable sharpener for the lead.

It also consists of certain details of construction and combination of parts, as will be more fully hereinafter set forth and pointed out in the claims.

The invention is clearly illustrated in the accompanying drawings, which form a part of this specification, in which—

Figure 1 represents a side view of a pencil with all the parts in place. Fig. 2 is a vertical longitudinal section of the same. Fig. 3 is a longitudinal section of the same taken at right angles to Fig. 2, and showing the sharpening device detached from the rear of the pencil and applied to the front thereof in the position it assumes when it is sharpening the lead. Fig. 4 is a detail view of the front sleeve or collar, with the clamp removed. Fig. 5 is a detail of the spring clamp, and Fig. 6 is a detail of the sharpening device.

Referring to the drawings now by letter, A represents the body of the pencil, which is longitudinally bored for the reception of the lead B, which fits loosely therein. Around the front portion of the body A fits a sleeve C, which has a bifurcated extension c which is tapered down at its end to closely encircle the lead B. This sleeve C is slotted as shown at c'.

D represents a lead gripping or clamping piece which fits over the end of the extension c of the sleeve C, and has projecting fingers d d with turned flanges or ends d' d'. These flanges have notched ends which fit into the slots c' c', to grip the lead, and by reason of

this construction, the sleeve C has a limited longitudinal movement in the slots c' c'.

At the rear of the body A is normally located the sharpening device. As shown, this consists of a sleeve or collar E preferably made of steel, which fits the end of the body A and is held thereto by friction. The outer end of this is tapered off and crimped as seen at e and thereby formed on its inside with a cone-shaped cutting or grinding surface. Surrounding the collar E is a sleeve F adapted to protect the pointed and roughened end e and also to receive and hold a rubber G.

The parts of the device are all normally disposed substantially as shown in Figs. 1 and 2, and from the foregoing description, it is thought the operation will be readily understood. In using the pencil the lead is drawn out by means of the clamp C and held in place during the writing operation by the slight natural pressure of the fingers on the fingers d d. When the writing is finished the lead is permitted to drop back into the body A. When the point of the lead becomes dull and rounded, and it is desired to sharpen it, the sharpener E is detached from the rear end of the body A and placed over the tapered portion c of the sleeve C, the lead having been previously drawn out and held by means of the clamping fingers d d moving in the slot c'. The sharpener is given a few turns and the lead is ground down to a point in the cone-shaped recess c. The sharpener is then returned to place and the pencil is ready for further use.

It will be seen that my arrangement is extremely simple, cheaply made and most convenient.

I have described my invention in its preferred form, but I wish it to be understood that I do not limit myself to the exact construction herein shown and described. Minor changes may be made therein without departing from the nature or spirit of the invention.

Having now described my invention, what I claim as new, and desire to secure by Letters Patent, is—

1. A lead pencil consisting of a body part in which the lead is loosely inserted, a metallic sleeve surrounding the body portion

having a bifurcated tapering extension with opposite slots therein, and a lead gripping or clamping device, consisting of a collar surrounding said tapering extension, having 5 fingers extending backwardly therefrom with inturned flanges thereon which fit into said slots and grip the lead, substantially as described.

2. The combination with a lead pencil of 10 the character described, of a sharpening device adapted to fit the end of said pencil, the same consisting of a collar having a portion

thereof crimped to form on its inner side a cone-shaped cutting or grinding surface, and a protecting sleeve surrounding said collar 15 and adapted to hold a rubber, substantially as described.

In testimony whereof I have signed this specification in the presence of two subscribing witnesses.

THOMAS F. HARRIS.
